DOUBLE WIRE CONNECTOR

Raymond H. Boardman, Hartford, Conn., assignor to The Hart Manufacturing Company, Hartford, Conn., a corporation of Connecticut

Application August 6, 1952, Serial No. 302,937

5 Claims. (Cl. 339—217)

This invention relates to electrical connectors and terminal assemblies and more specifically to a device for effecting a quick detachable connection between a first current conducting wire and a second current conducting wire.

The device of the present invention has particular utility for installations wherein it is desired to provide an easily attachable and easily releasable connection between two wire conductors. For example, the connector of this invention can be used in association with the terminal housing of heat control means for an electric range wherein the bus line conductor is to be connected to a plurality of current conducting wires such as the wires running to the heating elements of the range. In such installations, a plurality of connectors can be utilized in the construction of the terminal housing, each to detachably secure a current conducting wire to a common bus line.

It is the general aim of the invention to provide an economical, simple, and compact electrical connector of durable construction and which will provide means for detachably interconnecting a plurality of electrical conducting wires.

Another object of the invention is to provide an electrical connector which can be easily incorporated in the terminal housing construction for electric switches and the like and which requires no skilled technician to perform the assembly of the connector and the housing.

A further object of the invention is to provide a quick detachable connector and terminal housing assemblage which can be utilized in electrical installations to simplify the wiring thereof and to provide quick detachable means for connecting an electrical device to control means, a supply system, or to other electrical devices.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a fragmentary elevational view of a terminal housing assemblage including an electrical connector constructed in accordance with the present invention;

Fig. 2 is a cross-sectional view taken substantially as indicated by the line 2—2 of Fig. 1;

Fig. 3 is an enlarged cross-sectional view of the electrical connector removed from the terminal housing;

Fig. 4 is a sectional view taken as indicated by line 4—4 of Fig. 3;

Fig. 5 is a sectional view taken as indicated by the line 5—5 of Fig. 3; and

Fig. 6 is a perspective view of the spring member utilized in the connector construction.

A double wire connector 10 is shown in an assemblage which includes a terminal housing 12. The assemblage is particularly adapted for association with

2

the heat control switches for an electric range. The elements of the switch are not shown since the same comprise no part of the present invention. However, it should be understood that the arrangement is such that the housing 12 provides a rear cover for the switch mechanism with elements of the switch disposed within the hollow housing. It should also be understood that certain details of the construction to be described are incorporated to adapt the assemblage for the particular installation, but such details do not go to the essence of the invention and the disclosure of the details is merely for purposes of illustration.

The housing 12 is fabricated from electrical insulating material into a hollow body of generally rectangular configuration having relatively thin side walls 14 and 16 and a relatively thick connecting wall or rear wall 18. The wall 18 is provided with a plurality of spaced apart transverse cavities 20 which will accommodate the connector units 10. The cavities 20 are generally rectangular and the connectors 10 are disposed therein so as to be substantially flush with the surface of the wall 18. The lefthand side wall 14 is provided with a notch 22 in its upper edge adjacent each of the cavities 20 and a pair of notches 24 and 25 are similarly provided on the righthand side wall 16 adjacent each cavity. All of the said notches accommodate electrical conductors which are attached to the connector 10, as will appear in detail hereinafter.

The connector 10 is a two-piece unit comprising a frame 30 and a spring clip conductor 32 disposed within the frame. The frame per se is a sheet metal stamping which is bent to form a generally rectangular open-ended member having a bottom wall 34, side walls 36 and a longitudinally slotted top wall 38. The slot 40 in top wall 38 is defined by forming spaced apart downwardly extending flanges 42 on the opposite edges of the stamping and the flanges cooperate with the side walls 36 to define channels 44 and 46 on opposite sides of the slot.

The clip per se is an elongated spring steel stamping having spring arms 48 and 50 on opposite ends of the strip. The arms 48 and 50 are formed along the opposite longitudinal edges of the strip and are bent inwardly so as to engage at an acute angle the inner surface of frame wall 38 within the channels 44 and 46, respectively. The spring web or body 52 interconnecting the spring arms 48 and 50 engages against the bottom wall of the frame and the web is provided with a detent 54 which engages within an aperture 56 in the frame bottom to properly position the clip within the frame.

Spring arm 48 which is disposed within channel 44 is provided with a crimp 58 for engagement with frame wall 38 while arm 50 has a sharp edge 60 engaging the wall 38 in channel 46. As previously mentioned, the spring arms engage frame wall 38 at an acute angle and the angles in each instance open toward the adjacent end opening of the frame whereby electrical conducting wires such as the wires 62 and 64 may be inserted through the opposite ends of the frame to flex the arms inwardly and to be engaged between the arms and the frame wall 38. The wire 62 engaged by arm 48 within channel 44 may be shifted in either longitudinal direction since the crimp 58 does not grip or clamp the wire, but merely retains the wire in adjusted positions by frictional engagement therewith. However, wire 64 can be shifted in only one longitudinal direction, i. e. inwardly, since the edge 60 clamps the wire against longitudinal movement in the opposite direction.

Levers 66 and 68 are provided on spring arms 48 and 50, respectively, along the inner edges thereof and are arranged to extend upwardly through the slot 40 for manual operation and the flanges 42 are provided with

notches 69 to accommodate movement of the levers. Ears 70 are arranged on each of the levers to facilitate fingertip manipulation thereof. The levers provide readily accessible means for flexing the spring arms to permit longitudinal adjustment of wire 62 relative to arm 48 and to facilitate longitudinal movement of wire 64 in either direction relative to arm 50.

The aforescribed connector unit 10 is assembled with housing 12 by placing the same in one of the transverse cavities 20 with channel 44 aligned with notch 22. In this position the channel 44 will also be aligned with the lower notch 24 (in Fig. 1) adjacent the cavity, and the channel 46 will be aligned with the upper notch 25. In the said assembled position of the connector 10 within the housing 12, the frame wall 38 is substantially flush with the face of housing wall 18 and frame wall 34 is disposed against the bottom of cavity 20. A rivet 72 is passed through suitable apertures in the clip web 52, frame wall 34 and bottom of the cavity to secure the connector 10 in assembled relation within the housing cavity.

The foregoing assemblage will accommodate conducting wire 62 from either direction, i. e. the wire can be inserted within connector channel 44 through notch 22 or notch 24 and the wire can be shifted in either longitudinal direction. Insertion and adjustment of the wire may be facilitated by pressing lever 66 so as to flex spring arm 48 and thereby shift the crimp 58 from engagement with the wire. The wire 64 is connected to the assemblage by inserting the same in channel 46 through housing notch 25. While it is unnecessary to flex spring arm 50 to receive either a stranded or unitary wire within the channel, it is necessary to flex arm 50 before withdrawing the wire.

Accordingly, the assemblage described above provides quick detachable means for adjustably receiving and retaining a first conductor such as the wire 62 and quick detachable means for retaining a second conductor such as the wire 64.

The connector frame may be provided with a pair of posts 74 formed as downwardly and laterally extending legs on frame wall 34. In the assemblage shown in Figs. 1 and 2 the legs extend through slots 76 in the bottom of the housing cavity 20 so that the legs will be disposed in the hollow portion of the housing wherein elements (not shown) of a switch are disposed. Each of the slots 76 is provided with a sloped wall 78 to accommodate the legs in the lateral direction, but the opposite wall 80 of the slots is normal to the bottom of the housing cavity to prevent entry of the legs in the event an attempt should be made to improperly insert the connector within the cavity. This last-mentioned feature of construction makes the proper manner of assembly self-evident to even the most unskilled of persons.

It should be noted that the slots 76 are spaced apart at distances which vary from cavity to cavity in the housing 12 whereby the housing can accommodate a plurality of connectors, each having legs disposed within the hollow portion of the housing body in spaced relation to each other and spaced from the legs of the other connector units.

As previously mentioned, the assemblage described herein is particularly adapted to enclose elements of a switch for control for an electric range. A plurality of controls, as for various heating elements, the oven, etc., may be utilized in the installation whereby a plurality of the assemblages may be interconnected. Obviously, the interconnection of the assemblages to a common bus can be easily effected by inserting the bus line (wire 62) through the channels 44 in the connector units disposed in the respective assemblages.

In an interconnected arrangement of assemblages, the assemblages may be disposed in side-by-side relation, but regardless of the disposition or arrangement, the interconnecting or wiring of the assemblages is so simplified

in most cases as to be self-evident to one untrained in the art. In addition, much of the difficulty encountered in attaching electrical wires to terminal posts or terminal housings is eliminated since, to effect such connection with the present device, it is only necessary to extend the wires into the connector units through notches provided on the terminal housings. Disconnection is expedited by the incorporation of the manually operable retaining arms, which have the actuating levers disposed for fingertip manipulation adjacent the wires, whereby flexing of the arms may be easily accomplished to permit withdrawal of the wires from the connectors.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A quick detachable electrical connector comprising an open ended frame provided with a longitudinally slotted wall arranged to receive against its inner surface a longitudinally disposed conducting wire on each side of said slot, a clamping member disposed within said frame and having a pair of spring arms extending inwardly into engagement at an acute angle with said wall on opposite sides of said slot, each of said arms being arranged to hold a wire against said wall, an integral manual operating lever on each arm extending from the side edge of the arm outwardly through said slot, and laterally bent ears on the outer ends of the levers forming finger pieces for depressing the arms to release wires engaged thereby.

2. A quick detachable electrical connector comprising a generally rectangular open-ended frame provided with a longitudinally slotted wall, said wall having inturned flanges adjacent said slot defining a pair of longitudinal channels spaced on each side of the slot, a clamping member disposed within said frame having an inwardly bent spring arm disposed at one end disposed in one of the channels and an inwardly bent spring arm at the other end offset from the first-named arm and disposed in the other channel, said spring arms extending inwardly into engagement at an acute angle with said wall and arranged to hold a wire against said wall, and a manually operable actuating lever integrally upstanding from each of said arms and extending outwardly through said slot for flexing said arms further inwardly to release wires engaged thereby.

3. A quick detachable electrical connector comprising a generally rectangular open-ended frame provided with a longitudinally slotted wall, said wall having inturned flanges adjacent said slot to define a pair of longitudinal channels spaced on each side of the slot, a clamping member disposed within said frame and having a spring arm transversely disposed in each of said channels, each of said spring arms extending from a bending point inwardly into engagement at an acute angle with said wall on opposite sides of said slot and each of said arms being arranged to hold a longitudinally disposed conducting wire against said wall, one of said arms having a crimp for releasably retaining a conducting wire in adjusted positions and the other of said arms having a relatively sharp edge arranged to grip and hold a conducting wire against longitudinal movement in one direction, and a manually operable actuating lever integrally upstanding from each of said arms and extending through said slot for flexing said arms further inwardly to release wires engaged thereby.

4. An electrical terminal assemblage comprising an

insulating housing having an elongated cavity therein, said housing having a pair of notches at one end of the cavity and a single notch at the other end of the cavity, an open-ended frame disposed within said cavity and having an outwardly facing wall provided with a longitudinal slot, said wall being arranged to receive against its inner surface a conducting wire on each side of said slot, one of the conducting wires being insertable through one of said notches at said one end of the cavity or through the single notch at the other end of the cavity, and the other of the conducting wires being insertable through the other of said notches at said one end of the cavity, a clamping member disposed within said frame and having a pair of spring arms engageable at an acute angle with said wall on opposite sides of said slot, each of said arms being arranged to hold a wire against said wall, and a manually operable actuating lever on each of said arms extending outwardly through said slot for flexing said arms to release wires engaged thereby.

5. An electrical terminal assemblage comprising an insulating housing having a generally rectangular cavity therein, said housing having a pair of notches at one end of the cavity and a single notch at the other end of the cavity having an elongated cavity therein, said housing having a pair of notches at one end of the cavity and a single notch at the other end of the cavity, an open-ended frame disposed within said cavity and having an outwardly facing wall provided with a longitudinal slot, said wall being arranged to receive against its inner surface a conducting wire on each side of said slot, one of the conducting wires being insertable through one of said notches at said one end of the cavity or through the single notch at the other end of the cavity, and the other of the conducting wires being insertable through the other of said notches at said one end of the cavity, a clamping member disposed within said frame and having a pair of spring arms engageable at an acute angle with said wall on opposite sides of said slot, each of said arms being arranged to hold a wire against said wall, and a manually operable actuating lever on each of said arms extending outwardly through said slot for flexing said arms to release wires engaged thereby.

10

cavity and said housing having a plurality of slots at the bottom of said cavity, a generally rectangular open-ended connector frame having a pair of downwardly and laterally extending legs insertable within said slots when said connector frame is disposed within said cavity in one position, said connector frame being arranged to receive a first conducting wire extending through one of said pair of notches at one end of the cavity or through the notch in the other end of the cavity and a second conducting wire extending through the other of said pair of notches, and manually operable clamping means associated with said connector frame having a pair of spring arms for releasably clamping the wires received in the frame.
